D. E. ODOM

SPRING MOTOR

Filed Oct. 13, 1923

UNITED STATES PATENT OFFICE.

DANIEL E. ODOM, OF BENNETTSVILLE, SOUTH CAROLINA.

SPRING MOTOR.

Application filed October 18, 1923. Serial No. 668,302.

To all whom it may concern:

Be it known that I, DANIEL E. ODOM, a citizen of the United States, residing at Bennettsville, in the county of Marlboro and

5 State of South Carolina, have invented certain new and useful Improvements in Spring Motors, of which the following is a specification, reference being had to the accompanying drawings.

10 This invention relates to certain improvements in spring motors and it is an object of the invention to provide a novel and improved device of this general character wherein overwinding of the spring is prevented, the present invention being primarily an improvement of the embodiment of my invention as comprised in my pending application Serial No. 605,299 filed December 6, 1922.

15 It is also an object of the invention to provide a novel and improved device of this general character embodying a spring and a drum associated therewith wherein the tension of the spring normally maintains the same in driving connection with the drum and which connection constitutes an annular member fitting substantially snug within the drum and to which the spring is connected, said annular member and drum being provided with coacting means whereby the same are normally in locking engagement.

20 The invention consists in the details of construction and in the combination and arrangement of the several parts of my improved spring motor whereby certain important advantages are attained and the device rendered simpler, less expensive and otherwise more convenient and advantageous for use, as will be hereinafter more fully set forth.

25 The novel features of my invention will hereinafter be definitely claimed.

In order that my invention may be the better understood, I will now proceed to 30 describe the same with reference to the accompanying drawings, wherein—

Figure 1 is a sectional view taken through a motor constructed in accordance with an embodiment of my invention showing the 35 spring completely wound;

Figure 2 is a sectional view taken substantially on the line 2—2 of Figure 1;

Figure 3 is a fragmentary sectional view 40 illustrating another embodiment of my invention;

Figure 4 is a fragmentary sectional view

illustrating another form of my invention;

Figure 5 is a fragmentary sectional view 45 illustrating a still further embodiment of my invention;

Figure 6 is a sectional view taken substantially on the line 6—6 of Figure 5;

Figure 7 is a fragmentary sectional view 50 illustrating still another embodiment of my invention.

As disclosed in the accompanying drawings, D denotes a drum or driven member of requisite dimensions and which is mounted upon the shaft S, said drum D and shaft S having relative rotation under the instrumentality of the spring A. The spring A is of the conventional spiral type and has its inner end portion suitably fixed, as at 1, to the shaft S.

Fitting substantially snug within the 55 drum D is an annular member M possessing a certain degree of inherent resiliency and which, upon abnormal strain imposed thereon, is free to rotate independently of the drum. The wall of the member M is corrugated transversely entirely therearound whereby the outer face of the member M is provided circumferentially therearound with the spaced grooves or channels 2 extending circumferentially thereof. The adjacent 60 wall of the drum D is provided with a plurality of inwardly disposed projections 3 herein disclosed as three in number and equidistantly spaced. It is to be understood, however, that these projections may be more 65 or less in number as the requirements of practice may prefer.

As disclosed in Figure 1, these projections 70 constitute ribs or beads pressed out of the wall of the drum and disposed transversely thereof. Normally, the projections 3 are engaged within certain of the grooves or channels 2, such engagement being maintained by the inherent resiliency of the member M, said member being of such diameter 75 as to assure at all times frictional contact of said member M with the projections 3.

The outer end of the spring A is riveted or otherwise secured, as at 4, to the inner face of the member M.

In winding the spring A requisite rotation is imparted to the shaft S and after the spring A has been wound to its predetermined tension further rotation of the shaft will cause the member M to have movement independently of the drum D so that upon such further turning of the shaft S,

further winding of the spring is prevented. By this it will be understood that the winding action for the spring A becomes inactive when the strain imposed upon the spring A is greater than the resistance of the member M and the projections 3 to relative rotation.

In Figure 3, I disclose a form of my invention wherein the projection a constitutes a head or lug slidably disposed through the adjacent wall of the drum, said head or lug being constantly urged inwardly of the drum by the coil spring b. The coil spring b together with the major portion of the lug or head a is contained within a housing c carried by the drum.

The character of the projections carried by the drum D may be varied and as illustrated in Figure 4 such projections comprise a lug or head 5 freely disposed through a suitable opening 6 in the adjacent wall of the drum. The outer end of the head or lug 5 is provided with an outstanding shank 7 upon which is threaded or otherwise engaged a nut 8 or the like. A leaf spring 9 is secured at one end portion, as at 10, to the outer face of the wall of the drum while the opposite or free end portion of said spring bears against the nut 8 resulting in the head or lug 5 being constantly urged inwardly of the drum yet permitting the same to have requisite yielding movement to assure the proper functioning of the device. In order to facilitate the desired engagement of the spring 9 with the nut 8, said spring is provided with an opening 11 through which the shank 7 is freely disposed.

In the embodiment of my invention as illustrated in Figure 5, the projection 12 comprises a separable strip or cleat disposed transversely of the adjacent wall of the drum and provided with the longitudinally spaced outstanding shanks 14 disposed through suitably positioned openings in the wall of the drum, the outer end portions of said shanks 14 being upset, as at 15, to assure the proper maintenance of the member 12 in applied position.

In the embodiment of my invention as illustrated in Figure 7, the strip or cleat 12' has its outstanding shanks 14' freely disposed through the adjacent wall of the drum. Threaded through said wall of the drum and at a point substantially midway of the shanks 14' is a bolt 16 having its inner end contacting with the strip or cleat 12' whereby said strip or cleat 12' may be adjusted with respect to the adjacent wall of the drum in order to assure the proper functioning of the device. After the desired adjustment of the strip or cleat 12' has been effected, such adjustment is maintained by the locking nut 17 threaded upon the bolt 16 and coacting in a well known

manner with the adjacent wall of the drum.

From the foregoing description it is thought to be obvious that a spring motor constructed in accordance with my invention is particularly well adapted for use by 70 reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:—

1. In combination with two members supported for relative rotation, one of said members constituting a drum, a spiral spring having one end portion connected to the second of said members, an annular member fitting substantially snug within the drum, means for securing the other end of the spring to said annular member, said annular member being transversely corrugated entirely therearound whereby the outer face of said annular member is provided with recesses, and an inwardly disposed projection carried by the drum for engagement with any one of said recesses. 85 90 95

2. In combination with two members supported for relative rotation, one of said members constituting a drum, a spiral spring having one end portion connected to the second of said members, an annular member fitting substantially snug within the drum, means for securing the other end of the spring to said annular member, said annular member being transversely corrugated entirely therearound whereby the outer face of said annular member is provided with recesses, and an inwardly disposed projection carried by the drum for engagement with any one of said recesses 100 105 110 115 of the annular member, said annular member being resilient.

3. In combination with two members supported for relative rotation, one of said members constituting a drum, a spiral spring having one end portion connected to the second of said members, an annular member fitting substantially snug within the drum, means for securing the other end of the spring to said annular member, said annular member being transversely corrugated entirely therearound whereby the outer face of said annular member is provided with recesses, and inwardly disposed projections carried by the drum spaced circumferentially thereof for engagement with any of said recesses of the annular member, said annular member being resilient and constantly in frictional contact with the projections. 120 125 130

4. In combination with two members supported for relative rotation, one of said members constituting a drum, a spiral spring having one end portion connected to the second of said members, an annular member fitting substantially snug within the drum, means for securing the other end of the spring to said annular member, said annular member being transversely corrugated entirely therearound whereby the outer face of said annular member is provided with recesses, and an inwardly disposed projection carried by the drum for engagement with any one of said recesses of the annular member, said projection being slidably disposed through the wall of the drum, and means for urging said projection inwardly of the drum. 30

5 10 15 20 25

6. In combination with two members supported for relative rotation, one of said members constituting a drum, a spiral spring having one end portion connected to the second of said members, an annular member fitting substantially snug within the drum, means for securing the other end of the spring to said annular member, said annular member being transversely corrugated entirely therearound whereby the outer face of said annular member is provided with recesses, and an inwardly disposed projection carried by the drum for engagement with any one of said recesses of the annular member, said projection being movable with respect to the drum. 35 40 45 50

5. In combination with two members supported for relative rotation, one of said members constituting a drum, a spiral spring having one end portion connected to the second of said members, an annular member fitting substantially snug within the drum, means for securing the other end of the spring to said annular member, said annular member being transversely corrugated entirely therearound whereby the outer face of said annular member is provided with recesses, and an inwardly disposed projection carried by the drum for engagement with any one of said recesses of the annular member, said projection being removable from the drum. 50

20 25

In testimony whereof I hereunto affix my signature.

DANIEL E. ODOM.

In testimony whereof I hereunto affix my signature.

DANIEL E. ODOM.
